UNITED STATES PATENT OFFICE.

HEINRICH KOPPERS, OF ESSEN-RUHR, GERMANY.

INSTALLATION FOR DEGASIFYING NONCOOKING, BITUMINOUS MATERIALS AT LOW TEMPERATURE.

Application filed January 2, 1923. Serial No. 610,341.

To all whom it may concern:

Be it known that I, HEINRICH KOPPERS, a citizen of Germany, residing at Essen-Ruhr, Germany, have invented certain new and useful Improvements in Installations for Degasifying Noncoking, Bituminous Materials at Low Temperature (for which I have filed an application in Germany November 14, 1921), of which the following is a specification.

The degasifying of non-coking materials, i. e., of non-baking, bituminous materials often takes place in the so-called Rolle ovens, i. e. in cylindrical shaft ovens, in which the material to be distilled is forced, by means of a set of rings, superimposed like a jalousie or Venetian blind, so as to slide down along the heated walls in a thin layer; the gases produced thereby being enabled to freely enter into the interior through said jalousie-openings. The cylindrical form of the Rolle oven first has the disadvantage that any chokings of the sliding charge that occur in the interior of the oven cannot be observed and removed, because, owing to the closed shape of the oven, there is no possibility of observing and clearing such chokings or maintaining an action in the oven that will prevent such choking or stoppage of flow of the charge through the oven. On the other hand, the cylindrical form prevents the combining of a plurality of distillation chambers to obtain a unit as to construction and operation as is desirable for purposes of economical operation on a large scale.

According to the present invention, this limitation will be obviated by the fact, that the distillation of materials of the kind stated takes place within long rectangular chambers, on the long sides of which jalousie plates are arranged which abut against the front walls of said chambers.

The fresh material is thereby continuously fed from above through the openings existing between the jalousie plates and the heated walls of the distillation chambers, whilst the residue, low-temperature or Grude coke, is drawn off from below in a similar continuous manner. The ovens may be operated in a continuous manner without inter-

ruption, chokings or stoppage of the material therein due to the fact that the individual jalousie openings can be stirred in longitudinal direction with the help of poker bars, from the free front walls. Preferably this may be effected by means of continuously moved scrapers engaging said jalousie openings. By this means, on the one hand, the continuous downward movement, of the coal to be gasified, through the distillation chamber proper, is secured, whilst on the other hand the passages for the developed gases into the interior of said chamber are maintained free. Instead of reciprocating the scrapers, a similar effect might be produced by periodically stirring the jalousie framing.

The shape of the individual chamber thus given allows of a combination of a plurality of ovens so as to form a battery by simply juxtaposing the distillation chambers always separated by the heating walls. This offers the possibility to obtain a large output on a given area, as is of absolute necessity with technical working plants. At the same time, a constructional and operative compactness as well as the best conditions as to thermic economy are obtained.

In order to secure also the best conditions for the heating, particularly with regard to the development of a uniform and limited temperature, the gas and air are united at the lower end of a vertical combustion chamber, while the products of combustion are distributed, through an upper distribution channel, over the entire length of the individual heating walls and pass through said walls from above to below. By causing the combustion to take place outside of the oven walls, firstly the temperature-peaks are kept away from the distillation chamber, while the guiding of the hot gases from above to below within the heating wall proper, will secure, according to the law of Dichmann, the best conditions as to the heat transmission.

Jalousie frames have already been used with distillation chambers of rectangular cross section, operating interruptedly i. e. non-continuously, in order to obtain an outlet of the gases on the entire height of the

100

charge. By this means substantially the same result is obtained as in the likewise interruptedly operating vertical cokeovens and in the vertical retorts for producing 5 lighting gas, by applying a plurality of gas outlets distributed along the height of the chamber or retort. In any case there will result, as stated above, with continuous operation quite different working conditions 10 and quite as different effects.

In the drawing is illustrated an embodiment of the invention, Fig. 1 showing a longitudinal section, Fig. 2 a vertical cross section and Fig. 3 a horizontal cross section.

The individual distillation chambers 10, constructed of castiron plates, in the shape of a horizontal rectangular prism, are arranged side by side, in the same way as 20 coke-ovens, and separated by the heating chambers 11. Within the chambers 10 are provided the jalousie-like elements 12, by means of which the material, fed through the bunkers, is forced to glide down along 25 the walls of the chambers 10 in thin layers. Rotating feeders 14 at the lower end serve to convey the material into the outlets 15, from which they can be drawn through 30 ports 16. Owing to the jalousie-walls 12 extending on both side-walls of the chamber 10, these walls present a priori the property of being accessible from the front walls. This item, according to an improved 35 execution of the invention, is made use of by the fact that scrapers 17 united by a common bar 18 and extending like rakes over the entire height of the jalousies 12, are reciprocated to receive a to and fro movement from a drive 19, thus keeping 40 free the openings between the jalousies by their prongs engaging therein and so loosening the material resting therein, that it will glide evenly further downward.

The heating is performed in the following manner. In a recuperator 20 the combustion elements, gas and air or air only, are preheated before entering the vertical combustion chamber 21 and burn upwardly therein. The ascending current of flame 45 receives the impulse for further movement in a horizontal and in a downward direction. The gases entering in the horizontal channel 22 will first be distributed over the length of the same and then enter through 50 the nozzle-shaped tubes 23 in the interior of the heating wall proper 11. This heating wall is so large that the heating gases can 55 freely play therein i. e. they will descend by degrees forming numerous whirls, there- 60 by yielding their heat. Without any positive guiding being required with this current going from above to below, equal de- 65 grees of heat will establish in all layers. The tubes 23 serve to avoid excessive heat- ing of the upper portion of the heating

walls. In leaving the tubes 23, the hot gases, to wit, first will move upwards and intermix with the cooler gases, thus the temperature-peak will not work out its effect upon the heating wall itself.

70

Claims:

1. An installation for continuous distillation of non-coking bituminous materials at low temperature consisting of retort chambers of rectangular cross-section; heating walls for said chambers; jalousie walls arranged alongside said heating walls to force the materials to be distilled to move downward along the heating walls in thin layers.

75

2. An installation for continuous distillation of non-coking bituminous materials at low temperature, consisting of a plurality of distilling chambers of rectangular cross-section; heating walls contiguous to such distilling chambers and each interposed between two such distilling chambers; jalousie walls arranged alongside said heating walls to force the materials to be distilled to move downward along the heating walls in thin layers.

80

3. An installation for continuous distillation of non-coking bituminous materials at low temperature, consisting of a plurality of distilling chambers of rectangular cross-section; heating walls contiguous to such distilling chambers and each interposed between two such distilling chambers; jalousie walls arranged in said distilling chambers alongside the heating walls; combustion chambers remote from said distilling chambers; upper horizontally extending channels located above the heating walls and extending throughout the length thereof, said horizontally extending channels

85

communicably connecting said combustion chambers with the heating walls so that hot burned gases pass from the combustion chambers throughout the length of the heating walls and through said heating walls 100 from above to below.

105

4. An installation according to claim 3, characterized in that the hot gases are conducted from the upper distributing channel into the heating wall by means of nozzle-shaped tubes extending to a certain extent into said wall.

115

5. An installation according to claim 1, characterized in that said jalousie elements are subjected to a continuous influence to keep free the passages for the material to be distilled and the outlet for the gases by means of a mechanical drive.

120

6. An installation for continuous distillation of non-coking bituminous materials at low temperature, consisting of a plurality of distilling chambers of rectangular cross-section; heating walls contiguous to such distilling chambers and each interposed between two such distilling chambers; jalousie

125

130

- walls arranged alongside said heating walls; combustion chambers remote from said distilling chambers; upper horizontally extending channels located above the heating walls and extending throughout the length thereof; said horizontally extending channels communicably connecting said chambers with the heating walls; scrapers adapted to move in the openings provided by the 10 jalousie walls and means for moving said scrapers.
7. An installation for continuous distillation of non-coking bituminous materials at low temperature, consisting of a plurality of 15 distilling chambers of rectangular cross-section; heating walls contiguous to such distilling chambers and each interposed between two such distilling chambers; jalousie walls arranged alongside said heating walls; combustion chambers remote from said distilling chambers; upper horizontally extending channels located above the heating walls and extending throughout the length thereof; said horizontally extending channels communicably connecting said chambers with the heating walls; a plurality of rakes arranged throughout the area of the heating walls for moving the material between the 20 jalousie walls and the heating walls to keep clear the passages for the material to be distilled and the products of distillation; and a series of inter-connected rods to move said rakes as a unit; and devices for clearing 25 the distilled residue adapted to regulate the rate of movement through the distilling chamber of the material being distilled; and air tight receptacles below said clearing devices to receive the distilled residue, adapted 30 for intermittent withdrawal of the residue.
10. An installation for continuous distillation of non-coking bituminous materials at low temperature, consisting of a plurality of 35 distilling chambers of rectangular cross-section; heating walls contiguous to such distilling chambers and each interposed between two such distilling chambers; jalousie walls arranged alongside said heating walls to force the material to be distilled to move 40 downward alongside the heating walls; and means including a mechanical device for keeping free the passages for the material to be distilled and the outlet for the gases.
8. An installation for continuous distillation of non-coking bituminous materials at 45 low temperature, consisting of a plurality of distilling chambers of rectangular cross-section; heating walls contiguous to such distilling chambers and each interposed between two such distilling chambers; jalousie walls arranged alongside said heating walls; combustion chambers remote from said distilling chambers; upper horizontally extending channels located above the heating walls and extending throughout the length thereof; said horizontally extending channels communicably connecting said chambers with the heating walls; a plurality of rakes arranged throughout the area of the heating 50 walls for moving the material between the jalousie walls and the heating walls to keep clear the passages for the material to be distilled and the products of distillation; and a series of inter-connected rods to move said rakes as a unit; and devices for clearing 55 the distilled residue adapted to regulate the rate of movement through the distilling chamber of the material being distilled.
9. An installation for continuous distillation of non-coking bituminous materials at 60 low temperature, consisting of a plurality of distilling chambers of rectangular cross-section; heating walls contiguous to such distilling chambers and each interposed between two such distilling chambers; jalousie
- walls arranged alongside said heating walls; combustion chambers remote from said distilling chambers; upper horizontally extending channels located above the heating walls and extending throughout the length thereof; said horizontally extending channels communicably connecting said chambers with the heating walls; a plurality of rakes arranged throughout the area of the heating walls for moving the material between the jalousie walls and the heating walls to keep clear the passages for the material to be distilled and the products of distillation; and a series of inter-connected rods to move said rakes as a unit; and devices for clearing the distilled residue adapted to regulate the rate of movement through the distilling chamber of the material being distilled.
11. An installation for continuous distillation of non-coking bituminous materials at low temperature, consisting of a plurality of distilling chambers of rectangular cross-section; heating walls contiguous to such distilling chambers and each interposed between two such distilling chambers; jalousie walls arranged alongside said heating walls to force the material to be distilled to move downward alongside the heating walls; said jalousie elements being subjected to a continuous influence by means of a mechanical drive to keep free the passages for the material to be distilled and the outlet for the gases.
12. An installation for distilling non-coking bituminous material at low temperature, consisting of a straight distilling chamber having flat-faced walls; means for providing a thin layer passage adjacent said flat-faced walls, means for continuously supplying material to be distilled to said thin layer passage; means providing an outlet for the distilled vapors; means for discharging the residue of the distilled charge.
13. An installation for distilling non-coking bituminous materials at low temperature, consisting of a straight retort chamber having an extended flat-faced heating wall; means for continuously supplying material

to be distilled in a thin layer past said extended flat-faced walls, and means for removing the residue of distillation.

14. An installation for distilling non-coking bituminous material, consisting of a chamber having extended flat-faced heating walls; means in said chamber providing a thin passage alongside said heating walls; said means providing outlets for the dis-

tilled vapors; means continuously supplying material to be distilled to said passages, and means for maintaining said passages in condition for continuous movement of the material being distilled and for outlet of distilled vapors.

15. In testimony whereof I affix my signature.

HEINRICH KOPPERS.
